UNITED STATES PATENT OFFICE.

EMIL PIRCHAN, OF BERLIN-WILMERSDORF, GERMANY, ASSIGNOR TO HEINRICH KÜCHENMEISTER, OF BERLIN, GERMANY.

DESIGN FOR A CASING FOR TALKING MACHINES.

Application filed June 22, 1925. Serial No. 13,857. Term of patent 3½ years.

To all whom it may concern:

Be it known that I, EMIL PIRCHAN, a citizen of the Czechoslovak Republic, and a resident of Berlin-Wilmersdorf, Germany, have invented a new, original, and ornamental Design for Casings for Talking Machines, of which the following is a specification, reference being had to the accompanying drawing, forming part thereof.

In the accompanying drawing my improved design for a talking machine is shown in Figure 1 in side view and in Figure 2 in top plan view.

I claim:

The ornamental design for a casing for a talking machine, as shown.

In testimony whereof I affix my signature.
EMIL PIRCHAN.
